UNITED STATES PATENT OFFICE.

JOHN BEAN, OF HUDSON, MICHIGAN.

IMPROVEMENT IN PUMPS.

Specification forming part of Letters Patent No. 125,008, dated March 26, 1872.

To all whom it may concern:

Be it known that I, JOHN BEAN, of Hudson, in the county of Lenawee and in the State of Michigan, have invented certain new and useful Improvements in Pumps; and do hereby declare that the following is a full, clear, and exact description thereof, reference being had to the accompanying drawing and to the letters of reference marked thereon making a part of this specification.

My present invention is intended as an improvement upon the pump for which Letters Patent were granted to me February 9, 1869; and it consists in the suction and force buckets being so arranged that the suction-rod plays through the force-bucket with the water flowing up through the pipe which forms the force-rod, and in which the suction-rods plays, to the spout. It also consists in the combination, with the suction and force buckets thus arranged, of an air-chamber on the cylinder in such a manner that the air regulates for each bucket.

In order to enable others skilled in the art to which my invention appertains to make and use the same, I will now proceed to describe its construction and operation, referring to the annexed drawing, in which—

Figure 1 is a longitudinal vertical section of my improved pump, and Fig. 2 is an enlarged side view of the spout.

A represents the cylinder, in which are the suction-bucket B and the force-bucket C. The rod C' of the force-bucket is made of gas-pipe or any other suitable pipe, the upper end of which is pivoted to the handle D a short distance from the pivot-point of said handle. B' is the rod of the suction-bucket B, which rod

passes through the force-bucket C and the pipe C' and its upper end pivoted to the inner end of the handle D, both the bucket-rods being pivoted on the same side of the pivot-point of the handle. The water passes up through the center pipe C' and out through the spout E, connected with said pipe in any suitable manner. The force-bucket C moves about one-half the distance of the suction-bucket B, giving a steady stream of water with a powerful leverage on the water, working admirably in deep wells. Connected with the cylinder A is an air-chamber G, arranged as shown, so that the air will regulate for both buckets.

Having thus fully described my invention, what I claim as new, and desire to secure by Letters Patent, is—

1. The arrangement in one cylinder, A, of the suction-bucket B and force-bucket C, when the suction-rod B' passes through the force-bucket and its rod or pipe C', both being attached to the same end of the handle D and the water passing up through the center rod or pipe C', to and through the spout E, all substantially as herein set forth.

2. In combination with the cylinder A, buckets B C, and rods B' C', constructed and arranged as described, I claim the air-chamber G, arranged so that the air will regulate for both buckets, substantially as herein set forth.

In testimony that I claim the foregoing I have hereunto set my hand and seal this 1st day of February, 1872.

JOHN BEAN.
